US0D1003022S

(12) **United States Design Patent** (10) **Patent No.:** **US D1,003,022 S**
(45) **Date of Patent:** **** Oct. 31, 2023**

(54) **MID-SOLE CLEAT**

(71) Applicant: **Geroline Inc.**, St. Catharines (CA)

(72) Inventor: **Ryan DeCaire**, Toronto (CA)

(73) Assignee: **Geroline Inc.**, St. Catharines (CA)

(**) Term: **15 Years**

(21) Appl. No.: **29/762,895**

(22) Filed: **Dec. 18, 2020**

(30) **Foreign Application Priority Data**

Jun. 30, 2020 (CA) ..... CA 196629

(51) **LOC (14) Cl.** **02-04**

(52) **U.S. Cl.**

USPC **D2/962; D2/946**

(57) **CLAIM**

The ornamental design for a mid-sole cleat, as shown and described.

DESCRIPTION

FIG. 1 is a bottom isometric view of a first embodiment of a mid-sole cleat;

FIG. 2 is a bottom view thereof;

FIG. 3 is a right side view thereof;

FIG. 4 is a rear view thereof;

FIG. 5 is a left side view thereof;

FIG. 6 is a front view thereof;

FIG. 7 is a top view thereof.

FIG. 8 is a bottom isometric view of a second embodiment of a mid-sole cleat;

FIG. 9 is a bottom view thereof;

FIG. 10 is a right side view thereof;

FIG. 11 is a rear view thereof;

FIG. 12 is a left side view thereof;

FIG. 13 is a front view thereof; and,

FIG. 14 is a top view thereof.

The dot-dashed broken lines represent the environment of the claimed design and form no part of the claimed design. The even-dashed broken lines represent portions of the mid-sole cleat that form no part of the claimed design.

1 Claim, 8 Drawing Sheets
